UNITED STATES PATENT OFFICE.

ALDEN E. OSBORN, OF NEW YORK, N. Y.

INTERNAL-COMBUSTION ENGINE.

1,250,214.

Specification of Letters Patent. Patented Dec. 18, 1917.

Application filed November 13, 1914. Serial No. 871,865.

To all whom it may concern:

Be it known that I, ALDEN E. OSBORN, a citizen of the United States of America, and a resident of New York, county and State 5 of New York, have invented certain new and useful Improvements in Internal-Combustion Engines, of which the following is a specification, reference being had to the accompanying drawings, forming a part 10 thereof.

My invention relates to internal combustion engines, and has special reference to the valve mechanism thereof. In fact it pertains to valve mechanism of the general 15 character shown and described in U. S. Patents Nos. 985,198, 987,164 and 1,011,480 which have previously issued to me.

The object of my invention is to provide an improved mechanism of the character 20 above indicated that shall be simple and durable in construction and increase the power and efficiency of the engine with which it shall be used.

Other objects and advantages of my invention will be set forth hereinafter, and in order that my invention may be thoroughly understood I will now proceed to describe the same in the following specification and then point out the novel features thereof in 30 appended claims.

Referring to the drawings:

Figure 1 is a sectional elevation of an engine embodying one form of my invention.

35 A sectional plan view of the valve mechanism, taken on the line 2—2 of Fig. 1, is shown in Fig. 2.

Fig. 3 is a view corresponding to Fig. 1, of a slightly modified valve mechanism 40 which also embodies my invention.

Another modification is shown in Fig. 4, the views of Figs. 3 and 4 being drawn to a smaller scale than that of Figs. 1 and 2.

Still another modification of my invention 45 is shown in Fig. 5 which is a view corresponding to Fig. 1, and is drawn to the same scale.

Fig. 6 is a sectional elevation on a smaller scale, of an engine which is a slight modification of that shown in Fig. 5. This also 50 constitutes an embodiment of my invention.

Like characters of reference designate corresponding parts in all the figures.

The structure of Figs. 1 and 2 comprises

a cylinder 10, a piston 11 therein, a crank 55 casing 12, and a crank shaft 13 to which the piston is operatively connected by a rod 14.

The cylinder 11 is surrounded by a water jacket 15, and is enlarged at one side to form a valve cylinder 16 which is parallel 60 to the main cylinder. A piston valve 17 operates within the cylinder 16.

In addition to the piston valve there is a rotary valve 18, both of the valves 17 and 18 being driven from the crank shaft by 65 suitable gearing 20 shown in dotted lines in Fig. 1. The engine is provided with two admission ports 21 and 22 which are interconnected by a single supply pipe 23. An exhaust port 24 is located between the two 70 admission ports and communicates with an exhaust pipe 25 having two branches 26 and 27 which are located one on each side of the pipe 23.

The admission part 21 is governed by the 75 rotary valve 18 as well as the piston valve 17, while the port 24 is controlled solely by the piston valve 17, the port 22 being controlled by the main piston as well as the piston valve 17.

Either of the admission ports may be considered the principal port and the other the auxiliary port, but for convenience I will refer to the port 21 as the principal admission port and the port 22 as an auxiliary 85 admission port.

As clearly shown in Figs. 1 and 2, the valves 17 and 18 are both located so that they are not likely to become overheated and furthermore cooled by the water jacket. 90

Before describing the modified structure shown in the other figures, I will now describe the operation of the engine shown in Figs. 1 and 2.

Assuming that the parts occupy the positions in which they are shown in Fig. 1 and that a charge has just been compressed and fired, the piston 11 is now starting on its working stroke. At the end of this stroke the piston valve 17 which operates at one-half the speed of the main piston, has advanced one-half its stroke and uncovers the admission port 21. This port is closed, however, by the rotary valve 18 which operates at one-quarter the speed of the crank shaft. 100 During the exhaust stroke the piston valve 17 advances to the end of its stroke and opens the port 24, permitting the burnt gases 105

to be forced out. During the next stroke of the main piston which is the suction stroke, the rotary valve 18 is moved into its open position and the piston valve 17 is moved to uncover the port 22. The auxiliary opening 22 is, however, not open into the cylinder until the main piston approaches the end of its stroke. By this means an amount of fresh gas is admitted to the cylinder in addition to that admitted through the port 21.

The next stroke is the compression stroke during which the admission ports 21 and 22 are closed and the piston valve 17 is returned to the position shown in Fig. 1. The engine 15 is again fired and the cycle is repeated. The parts are so arranged that the auxiliary admission port is not opened at the end of the working stroke.

While the auxiliary admission port 22 receives its supply from the pipe 23 which also supplies the main admission port 21, these ports may be supplied separately as shown in the slightly modified structure of Fig. 3. The ports 21 and 22 are here independent of 25 each other and may be supplied from independent sources.

Corresponding parts are here designated by the same reference characters as those used in Figs. 1 and 2.

Another modification of my invention is shown in Fig. 4 in which there is an admission port 30 which corresponds to the port 21 of the previous figures. The piston valve 31 which corresponds to the valve 17 instead of 35 being provided with a transverse passage 22 for completing the auxiliary admission opening, is provided with a hollow chamber or recess 32 which is adapted to register with an auxiliary admission opening 33 at the 40 end of the suction stroke, thereby providing an auxiliary admission from the crank casing 15 through the recess 32 and the opening 33. The exhaust is completed through the valve cylinder and a port 34 which corresponds to the port 24. The operation of this 45 arrangement is the same as that described for the structure of Figs. 1 and 2, except that the auxiliary admission is supplied from the crank casing into which a charge of gas or 50 air is drawn and may be compressed in a well known manner by the main piston.

Referring to Fig. 5 of the drawings, still another arrangement is here illustrated which comprises a cylinder 40 in which operates a main piston 41, a crank casing 42, a crank shaft 43 therein, connected to the piston by means of a rod 44, a valve piston 45 located in the end of the main cylinder, and suitable gearing for actuating the valve piston 46 at one-half the speed of the main piston. The cylinder is provided with two admission ports 46, 47 which are respectively governed by rotary valves 48 and 49. A single supply pipe 50 may be utilized as shown in 65 the drawings, or separate supply pipes may

be substituted if desired. Both of the rotary valves 48 and 49 operate at one-fourth the speed of the crank shaft. The piston valve 45 is operatively connected to a valve crank shaft 51 which is driven from the main crank shaft 43 by means of a sprocket chain 52 and sprocket wheels 53 and 54. The rotary valves 48 and 49 are connected to the valve crank shaft 51 by gears 55, 56 and 57.

The operation of this structure is as follows: The compressed charge is exploded with the valves and piston in the positions in which they are illustrated. During the working stroke which follows, the piston valve 45 is moved backwardly and uncovers the opening 58 of the admission port 46. The rotary valve 48, however, is closed so that the port is not open. The next stroke is the exhaust stroke and is accompanied by a further movement of the piston valve 45 in the same direction which uncovers the exhaust port 59 and permits the burnt gases to escape. During the suction stroke the piston valve returns sufficiently to cover the exhaust port but not to cover the opening 58, the admission port now being opened by the rotary valve 48. The auxiliary admission port is also opened by the rotary valve 49, the port being uncovered by the main piston just at the end of this stroke. The 95 parts occupy the positions shown in Fig. 5 at the end of the next stroke, which is a compression stroke. The cycle is repeated as the engine continues to operate.

The modified arrangement of Fig. 6 is 100 similar in some respects to the arrangement of Fig. 5 and in other respects it resembles the arrangement of Fig. 1. It comprises a piston valve 60, operating in a cylinder 61 parallel to the main cylinder 10 and has an 105 extension 62 to which another piston valve section 63, which operates in the main cylinder 10, is secured by means of an arm 64. The piston valve 60 has a through passage 65 which corresponds to the passage 22 in 110 the piston valve 17 of Fig. 1 and in a similar manner co-operates with the auxiliary port 66. In operation the main admission and exhaust ports are controlled as in the structure of Fig. 5 and the auxiliary port is 115 arranged so as to be opened during the desired stroke. The piston valve section 63 corresponds to the piston valve 45 of Fig. 5 and controls the main admission port 67 and the exhaust port 68, corresponding 120 respectively to the ports 46 and 59. The admission port 67 is also controlled by a rotary valve 70 corresponding to the valve 48.

To summarize in conclusion, my improved valve mechanism is adapted to be utilized 125 to provide for admission of fuel into an auxiliary port from the main inlet pipe as shown in Fig. 1; the admission of fuel into the auxiliary port from a separate inlet pipe as shown in Fig. 3, or the admission of fuel 130

or air into an auxiliary port from the crank case as shown in Fig. 4. Furthermore, it is evident that the auxiliary port may be controlled either by the piston valve as shown in Figs. 1, 3 and 4, or a rotary valve as shown in Fig. 5. The auxiliary port may be controlled by a part of the valve which controls the main ports, as shown in Figs. 1, 3 and 4, or by a separate valve as shown in Fig. 5.

It should be understood that the principal admission port may be used as an exhaust port while the exhaust port is used as an admission port as this reversed connection of the inlet and exhaust is perfectly operative when the direction of rotation of the valve crank shaft is also reversed and is desirable under certain conditions. Thus in the form of my invention shown in Fig. 1 the port 24 may be in communication with the fresh inlet charge through the pipe 25 while the ports 21 and 22 may be for the exhaust gases which can pass away through the pipe 23, a portion of these gases passing through the valve 18.

Various other structural modifications may be effected within the spirit and scope of my invention and I intend that only such limitations be imposed as are indicated in the appended claims.

What I claim is:

1. In an internal combustion engine, a main cylinder, a piston operating therein, a valve cylinder communicating with the main cylinder at one end, a piston valve within the valve cylinder, and main and auxiliary admission ports and an exhaust port all controlled by said piston valve.

2. In an internal combustion engine, a main cylinder, a piston operating therein, a valve cylinder communicating with the main cylinder at one end, a piston valve within the valve cylinder, main and auxiliary admission ports near opposite ends of the valve cylinder, and an exhaust port between the admission ports all controlled by said piston valve.

3. In an internal combustion engine, a main cylinder, a valve cylinder adjacent and parallel thereto and opening into a common chamber at one end, a piston in the main cylinder, a piston valve in the valve cylinder, means for reciprocating the piston valve at one-half the speed of the main piston, an auxiliary admission port connecting the main cylinder and the valve cylinder, a main admission port communicating with the valve cylinder adjacent to the said common chamber, a rotary valve for controlling the main admission opening, and an exhaust port, said piston valve being arranged to govern all of said ports.

4. A valve mechanism for an internal combustion engine comprising a slide valve, main and auxiliary admission ports con-

trolled thereby and opening into the cylinder at different points in the piston stroke, and a second valve controlling the main admission port in conjunction with the slide valve to open said port after it has been 70 uncovered by the slide valve.

5. In an internal combustion engine, a cylinder, a piston operating therein, a chamber at the end of the cylinder, an admission port and an exhaust port adapted to be connected to said chamber, an auxiliary admission port connected to said cylinder in position to be uncovered when the piston approaches the end of its stroke and a valve independent of the cylinder for controlling 80 all of said ports, said valve being adapted to close the auxiliary admission port at the end of the working stroke.

6. A valve mechanism for an internal combustion engine comprising a slide valve, 85 an exhaust port and main and auxiliary admission ports controlled by the slide valve, and a second valve controlling one of said admission ports in addition to the slide valve and a single admission pipe connected to 90 both said main and said auxiliary admission ports.

7. A valve mechanism for an internal combustion engine comprising a cylinder, a chamber opening into the cylinder at one 95 end, a piston operating in the cylinder, an auxiliary admission port adapted to be uncovered by the piston at the end of its outward stroke, a main admission port communicating with said chamber, a slide valve 100 independent of the cylinder for governing the main and auxiliary admission ports, a crank operatively connected to said piston, a crank casing inclosing said crank and having an opening governed by the slide valve, 105 said slide valve being adapted to connect said auxiliary admission port to said crank casing when said port is uncovered at the end of the suction stroke.

8. A valve mechanism for an internal combustion engine comprising a cylinder, a chamber opening into the cylinder at one end, a piston operating in the cylinder, an auxiliary admission port adapted to be uncovered by the piston at the end of its outward stroke, a main admission port communicating with said chamber, a slide valve independent of the cylinder for governing the main and auxiliary admission ports, a crank 115 operatively connected to said piston, a crank casing inclosing said crank, said slide valve being adapted to connect said auxiliary admission port to said crank casing when said port is uncovered at the end of the suction stroke, and a rotary valve for coöperating 120 with the slide valve to govern the main admission port.

9. In an internal combustion engine, the combination with a cylinder, three independent ports therefor, a power piston 130

adapted to reciprocate in the cylinder, valve means and an auxiliary valve adapted to open and close one of said ports, said valve means being adapted to independently control a second of said ports and to control the third port in conjunction with the power piston.

10. In an internal combustion engine, the combination with a cylinder, three independent ports therefor, a power piston adapted to reciprocate in the cylinder, a main valve and an auxiliary valve adapted to open and close one of said ports, said main valve being adapted to control a second of said ports in conjunction with the power piston.

11. In an internal combustion engine, the combination with a cylinder, three independent ports communicating therewith, a power piston adapted to reciprocate in the cylinder, a main valve adapted to control all of said ports, and an auxiliary valve

adapted to coöperate with the main valve in controlling one of said ports.

12. In an internal combustion engine, the combination with a cylinder, three independent ports communicating therewith, a power piston adapted to reciprocate in the cylinder, a main valve adapted to control all of said ports, and an auxiliary valve adapted to coöperate with the main valve in controlling one of said ports, said power piston being adapted to coöperate with the main valve in controlling another of said ports.

In testimony whereof I have hereunto set my hand this 11th day of November, 1914, in the presence of two subscribing witnesses.

ALDEN E. OSBORN.
